VISUALIZING DEVICE.

Application filed May 5, 1925. Serial No. 28,174.

Our invention relates to improvements in visualizing devices, the objects of which are to provide means whereby an article intended for personal wear may be visualized in the desired position upon the person in the reflected image of the wearer, such as for instance a person being fitted with false teeth, such teeth may be well selected by viewing them in proper position 10 of the mouth in the reflected image of the wearer, and in a like manner a tie or other article of wearing apparel may be visualized in position, thereby rendering proper selection simple.

15 The invention consists essentially of a mirror having an unsilvered space thereon conforming approximately to the article to be selected and means for displaying the article in a plane to the rear of the mirror, as will be more fully described in the following specification in which:—

Fig. 1 is a sectional view of the invention showing its application for dental use.

Fig. 2 is an elevation.

25 Fig. 3 is an elevation of the device as adapted to another use.

In the drawings like characters of reference indicate corresponding parts in each figure.

30 The numeral 1 indicates generally a mirror in which 2 is the glass, 3 is the silvered rear surface and 4 an aperture therein, which is shaped to conform substantially to a portion of the mouth when open. Secured at the rear of the mirror and registering with the aperture 4 is an open ended tube 5 which is flared outwardly to the rear so that its inner surfaces are not visible to the eye when the device is in use. Attached to the upper and lower sides respectively of the tube are slides or clips of any suitable type which are indicated by the numerals 6 and 7, in which a strip of wax 8 having one or more sample teeth 9 mounted upon it or a sample plate, are held. The clip 6 being used for displaying upper dental work and the clip 7 for lower dental work.

45 In Figure 3 the mirror is shown with an

elongated aperture 10 through the silvered 50 surface to conform to the shape of a tie, so that a fabric may be displayed therethrough to represent a tie of that fabric.

Having thus described the several parts of our invention we will now briefly explain its use.

When it is desired to fit a patient with lower teeth, samples of teeth approximating the natural teeth and suitably mounted upon a strip of wax 8 are held in position by the clip 7 of the tube 5, the patient then holds the mirror 1 in the approximate position shown in solid lines in Figure 1 while looking through the tube at the artificial teeth and at the same time holding his mouth open, 60 he then tilts the mirror until the artificial teeth assume the relative position in the reflection on the mirror as they would occupy in his mouth. When this position is reached, the upper border of the aperture 4 is low 70 enough to reflect the patient's natural upper teeth in the mirror, so that the matching of the artificial with the natural teeth can be effectively performed.

If artificial teeth are to be shown in the upper jaw the selection is fitted in the clip 6 and the mirror and is held in a position approximating that shown in dotted line in Figure 1.

What we claim as our invention is:

1. A visualizing device comprising a reflecting surface having an aperture approximating the outline of an article adapted for personal wear to be displayed and means for supporting the article whereby the article appears in its appointed position on the image of the person as reflected upon the reflecting surface.

2. A visualizing device comprising a reflecting surface having an aperture, a tube 80 extending rearwardly from the surface and of a size greater than said aperture, and means at the outer end of the tube for supporting an article adapted for personal wear whereby the article appears on the image 85 of the person as reflected upon the reflecting surface.

3. A visualizing device comprising a re-

flecting surface having an aperture, a tube extending rearwardly from the surface and of a size greater than said aperture, said tube being of greater cross sectional area at its outer end than at its point of connection with the reflecting area, and means at the outer end of the tube for supporting an

article adapted for personal wear whereby the article appears on the image of the person as reflected upon the reflecting surface. ¹⁰

Dated at Vancouver, B. C., this 21st day of April, 1925.

GEORGE RALEIGH PRICE.

FRANCIS TILDEN RICHARDSON.
